CARBURETOR FOR INTERNAL COMBUSTION ENGINES

Pablo August, Buenos Aires, Argentina

Application April 1, 1958, Serial No. 725,589

11 Claims. (Cl. 261—41)

This application is a continuation-in-part of my pending application Serial No. 598,811, filed July 19, 1956 and now abandoned, wherein I have described an improved carburetor for internal combustion engines comprising a shut-off device for immediately interrupting the fuel supply to the engine when the throttle valve is closed.

My present invention refers to certain further new and useful improvements in carburetors aiming at not only economizing fuel, but also avoiding a dilution of the lubricating oil in the working cylinders and ensuring a perfect lubrication of the working pistons and cylinder even when, for instance, a motor car moves down hill and drives the motor.

The main object of my invention is to provide an improved carburetor for internal combustion engines comprising in combination with a mechanically operated shut-off device provided in the main fuel system a vacuum-operated shut-off device in the idling system connected with a source of oil-saturated air and so arranged that when closing the throttle valve, the fuel supply is practically at the same time interrupted in both the main fuel system and the idling system and during these periods of fuel-supply interruptions oil-saturated air for lubricating the working piston and cylinder is sucked in by the engine as long as it continues operating.

One object of the invention is to provide an improved carburetor, comprising in its main fuel system a mixing tube in communication with the usual float chamber, provided with fuel-outlet ports and with an air-inlet spring-loaded nozzle member movably arranged in said mixing tube for closing said outlet ports, a lever means operatively connected by a mechanical motion-transmitting system with the usual throttle valve of the carburetor and arranged for pushing said nozzle member into its closing position when said throttle valve is closed, a vacuum-operated piston provided within a corresponding cylinder which is connected by channel means with the outlet of the carburetor below its throttle valve, with the usual fuel-supply means of the idling system, with the said mixing tube of the main fuel system and with a source of oil-saturated air, said channel means including a circumferential groove of said piston and being under the control of this piston which on the one hand is operated by a spring member and on the other hand by a partial vacuum produced by the engine, with the advantageous result that when the usual throttle valve of the carburetor is closed the said spring-loaded nozzle and the said control piston are moved to their fuel-shut-off position in which this control piston at the same time opens a connection with a source of oil-saturated air and permits the engine while still running to suck in such oil-saturated air for lubrication purposes.

With these objects and advantageous features in view my present invention comprises the arrangement, combination and construction of parts as will be hereinafter fully described with particular reference to the accompanying drawings, wherein:

2

Fig. 1 is a schematic vertical sectional view of a carburetor for internal combustion engines according to the invention incorporating shut-off devices for interrupting the fuel supply through both the main fuel system and the idling system of the carburetor; in this figure the known parts of the idling system have been omitted and only the novel shut-off device of the same has been shown;

Figures 2 and 3 are two enlarged vertical sectional views of the shut-off device of the idling system in two different embodiments of the invention;

Figure 4 is a cross sectional view along the line 4—4 of Figure 2;

Figure 5 is an elevation of the carburetor as seen from behind, showing the mechanical connection between the usual throttle valve of the carburetor and the control means of the shut-off device of the main fuel system.

The main fuel system of the carburetor comprises a mixing chamber 1 with the air inlet 2, the venturi tube 3 and the air outlet 4 containing the usual throttle valve 5.

The mixing chamber 1 contains a tubular supporting member 6 which is closed at its lower end and into which at 7 opens a fuel-supply channel from the float chamber 8, said supporting member carrying a mixing tube 9. This tube 9 is provided at its upper end with two lateral fuel-outlet ports 10 and at certain small distance below said ports 10 forms an internal shoulder 11, whereas immediately above said ports 10 forms an annular flange 12 for supporting a helical spring 13 which surrounds the tube 9 and with its upper end abuts against a flange 14 of a mixing nozzle 15. The upper end of this nozzle conveniently comprises inserted therein a throttle member 16, whereas its lower end carries a perforated tube formed as a tubular extension 16' of smaller diameter. Whereas the nozzle member 15 snugly fits in the upper portion of the tube 9, said tubular extension 16' freely projects into the lower portion of said tube 9. The arrangement of the nozzle member 15 is such that it is normally held in its lifted position as shown maintaining the outlet ports 10 open, but closed these ports when it is moved down-wards by means of a lever 17 until resting on the shoulder 11.

The lever 17 is secured to a shaft 18 which at the outside has fixedly mounted thereon an arm 19 (Fig. 5), and this arm 19 is connected by a rod member 20 with an arm 21 secured to the shaft 22 in such an arrangement that when the throttle valve 5 is closed in the usual manner the lever 17 moves the nozzle member 15 down-wards, closes the fuel-outlet ports 10 and thus instantaneously shuts-off the fuel supply through the main system of the carburetor.

The idling system has not been shown in as far as details of known construction are concerned. The shut-off device of said system according to the invention comprises a casing 23 (Fig. 2) which conveniently forms part of the carburetor body 1 (Fig. 5) and has a cylinder 24 inserted and fixed therein. The cylinder 24 contains a movable piston 25, an upper ring member 26 and a lower ring member 27, an upper packing ring 28 and a lower packing ring 29. The piston rod 30 extends through the upper ring member 26 and is surrounded by a helical spring 31, the pressure of which may be regulated by a screw 32 in combination with a washer 33. The top surface of the piston 25 cooperates with the upper packing ring 28 to make a tight seal in its upper position. The lower end of the piston 25 is formed with a conical recess so as to provide an annular surface 34 capable of making an air-tight seal with the packing ring 29.

The chamber 35 is permanently communicated through the ring member 27 and a channel 36 (Fig. 1) with the outlet 4 of the carburetor with the result that, when the throttle valve 5 is closed, the partial vacuum pro-

duced by piston of the working cylinder will become effective in the chamber 35 and will cause the piston 25 to move from its upper to its lower position.

The reference numeral 37 (Fig. 4) indicates the fuel channel of the idling system. The channel 37 registers with a transversal slot 38 of the cylinder 24 which comprises a similar slot 39 at a substantially diametrically opposite point. This second slot 39 is in communication with a tangential channel 40 and the two slots 38, 39 are interconnected by a circumferential groove 41 of the piston 25, the arrangement being such that, when the piston 25 is in its upper position as shown, the fuel supplied by the usual mixing nozzle of the idling system (not shown) may freely pass by way of said groove 41 to the working cylinder of the engine.

Below the slot 39 there is provided a channel 42 and the groove 41 is so broad that, when the piston 25 is in its lower position, it will interconnect the channels 39 and 42, interrupting at the same time the communication between the slots 38, 39 due to that the slot 39 is arranged at a lower level than the slot 38 as shown in Fig. 2.

The channel 42 is connected by means of a pipe member 43 with a suitable source of oil vapor or oil saturated air such as the crank case of the engine, the arrangement being such that when the piston 25 is in its lower position and interrupts the fuel supply through the idling system, the engine will suck in oil vapor or oil-saturated air by way of the pipe 43, channel 42, groove 41 and fuel-outlet channel 40.

The embodiment as shown in Fig. 3 differs from that of Fig. 2 insofar as the channel 42 is omitted and a channel 44 connects the channel 40 with the interior of the cylinder 24 at short distance from the upper ring member 26. In this arrangement the two slots 38, 39 are situated at substantially the same level. Further, in this embodiment the upper ring member 26 carries a tube 45 conveniently of transparent material inserted into an upper extension of the cylinder 24 and provided at its upper end with a neck portion 46 for the connection of a rubber hose (not shown) leading to a suitable source of oil vapor or oil-saturated air (not shown), the arrangement being such that, when the piston 25 is in its lower position and interrupts the fuel supply through the idling system, the engine will suck in oil vapor or oil-saturated air by way of the tube 45, the annular space between piston rod 30 and ring member 26, channel 44 and fuel-outlet channel 40, and that said oil vapor or oil-saturated air will perfectly lubricate the engine, for instance, when a car moves down-hill and the fuel supply through the main system of the carburetor and its idling system are closed, but the engine continues running for being operated by the car.

The shut-off device of the idling system as shown in Figures 2 and 3 is very efficient. The channels of the idling system must have an inner diameter of 3-3.5 mm. In order to perfectly close such a circular cross section the piston stroke must be at least of 4 mm. By virtue of that in accordance with the invention the cylinder 25 is provided with slots 38, 39 of a length of about 8 mm. and the channels 37 and 40 extend in tangential direction with regard to said slots, the width of the latter may be reduced to 1 mm. and the piston stroke to 1.5 mm. only. In this manner my present invention provides a very efficient and exactly operating shut-off device capable of reducing the fuel consumption of the engine.

The operation of the improved carburetor according to my present invention is shortly as follows:

As soon as the driver of a car closes the throttle valve 5, by means of the mechanical connection comprising the arm 21, rod 20, arm 19, shaft 18 and lever 17, the nozzle 15 is moved downwards and closes the fuel-outlet ports 10 thereby interrupting the fuel supply through the main fuel system of the carburetor. Simul-

taneously the suction produced by the working piston of the engine causes the piston 25 to move downwards and to also interrupt the fuel supply through the idling system, opening at the same time the connection with a source of oil vapor or oil-saturated air so that the engine receives the required oil for its lubrication, for instance, when the car moves down-hill and operates the engine.

What I claim as new and desire to secure by Letters Patent is:

1. A carburetor with a float chamber, a main fuel system and an idling system for internal combustion engines, comprising a mixing chamber with an air inlet, a venturi tube formed in said chamber, a fuel nozzle connected with said float chamber and surrounded by said venturi tube, and a mixture outlet containing the usual throttle and having a flange for its connection with the intake of an internal combustion engine, a first fuel-shut-off device provided in connection with said fuel nozzle in said main fuel system and a second fuel-shut-off device in said idling system, both of said shut-off devices being dependent of the operation of the throttle valve in said mixture outlet, said second shut-off device comprising a cylinder having a piston-like valve body movably arranged therein, there being channels in the wall of said cylinder and in said piston controlled by the latter and capable of communicating said float chamber with an outlet of said idling system connected in turn with said mixture outlet of said mixing chamber with said float chamber, respectively with an intake port of said cylinder for oil-saturated air.

2. A carburetor with a float chamber, a main fuel system and an idling system for internal combustion engines, comprising a mixing chamber with an air inlet, a venturi tube formed in said chamber, a fuel nozzle connected with said float chamber and surrounded by said venturi tube, and a mixture outlet containing the usual throttle and having a flange for its connection with the intake of an internal combustion engine, a first fuel-shut-off device provided in connection with said fuel nozzle in said main fuel system and a second fuel-shut-off device in said idling system, both of said shut-off devices being dependent on the operation of the throttle valve in said mixture outlet, the shut-off device of said main fuel system comprising a mixing tube having a movable spring-loaded nozzle member arranged therein, there being fuel-outlet ports in said mixing tube and controlled by said nozzle member, a lever operatively connected by a mechanical motion-transmitting system with said throttle for controlling said nozzle member, said second shut-off device comprising a cylinder having a piston-like valve body movably arranged therein, there being channels in the wall of said cylinder and in said piston controlled by the latter and capable of communicating said float chamber with an outlet of said idling system connected in turn with said mixture outlet of said mixing chamber with said float chamber, respectively with an intake port of said cylinder for oil-saturated air.

3. A carburetor for internal combustion engines as set forth in claim 2, wherein the said spring-loaded nozzle member comprises a main tubular upper portion for controlling the said fuel-outlet ports of the said mixing tube, and a perforated tubular extension of smaller diameter constituting a mixing tube within said mixing tube.

4. A carburetor for internal combustion engines as set forth in claim 2, wherein the spring-loaded nozzle member includes a throttle member arranged within the upper free end of the same.

5. A carburetor for internal combustion engines as set forth in claim 2, wherein the said piston-like valve body comprises a circumferential groove and the said cylinder containing said piston is provided with transversal slots in direct communication with tangential fuel-inlet and

outlet channels of the said idling system, said tangential channels being formed in the walls of a casing surrounding said cylinder.

6. A carburetor for internal combustion engines as set forth in claim 2, wherein the said inlet port for an oil-saturated air is connected with the outlet of the idling system by way of a perforation of a casing surrounding the said cylinder of the said shut-off device of said idling system and of a registering perforation of said cylinder which in turn is connected with said outlet by way of a circumferential groove of the said piston in said cylinder when said piston is in its lower position.

7. A carburetor for internal combustion engines as set forth in claim 2, wherein the said inlet port for an oil-saturated air is formed by a neck portion of a tube surrounding the rod of the said vacuum-operated piston and being in turn connected with the outlet of the said idling system by way of the interior of the said cylinder containing said piston and of a channel formed in the walls of said cylinder and of a casing surrounding the latter.

8. A fuel-shut-off device for the idling system of carburetors for internal combustion engines, comprising a cylinder connected with the fuel inlet and outlet of said idling system, a vacuum-operated spring-loaded piston in said cylinder for controlling said inlet and outlet, a pair of relatively long and narrow transversal slots provided in the wall of said cylinder within reach of a circumferential groove of said piston and a pair of channels arranged in tangential relation to said slots and in direct communication with the latter, said channels forming parts of said fuel inlet and outlet.

9. A fuel-shut-off device for the idling system of carburetors for internal combustion engines, comprising a cylinder, a pair of substantially opposite transversal relatively long and narrow slots provided in the wall of said cylinder for its connection with the fuel inlet and outlet of said idling system, a vacuum-operated spring-loaded piston in said cylinder for alternatively closing said slots and interconnecting the latter by way of a circumferential groove of the piston body, a pair of ring members fixed in the open ends of said cylinder and provided respectively for the protrusion of a rod of said piston and for the communication of the interior of said cylinder with a suction channel leading to the outlet of the carburetor below its throttle valve, and a pair of packing rings arranged on the inner surfaces of said ring members for co-operation with said piston in air-tight sealing the cylinder ends.

10. A fuel-shut-off device for the idling systems of

50

carburetors for internal combustion engines, comprising a cylinder having open ends and being provided with a pair of substantially opposite relatively long and narrow slots cut into the wall of said cylinder for its connection with a pair of channels leading tangentially to said slots and forming parts of the fuel inlet and outlet of said idling system, a vacuum-operated spring-loaded piston arranged in said cylinder and provided with a circumferential groove for interconnecting said slots, a pair of ring members fixed in the open ends of said cylinder and a pair of packing rings provided on the inner surfaces of said ring members for co-operation with said piston in air-tight sealing said cylinder ends, one of said slots which is in direct communication with the fuel-outlet channel being arranged on a slightly lower level than the other slot connected with the fuel-inlet channel, and an opening provided in the cylinder wall at short distance below said first-mentioned slot, the said circumferential groove of said piston being of sufficient width to alternatively interconnect said two slots and said first-mentioned slot with said opening.

11. A fuel-shut-off device for the idling system of carburetors for internal combustion engines, comprising a cylinder having open ends and being provided with a pair of substantially opposite relatively long and narrow slots cut into the wall of said cylinder for its connection with a pair of channels leading tangentially to said slots and forming parts of the fuel inlet and outlet of said idling system, a vacuum-operated spring-loaded piston arranged in said cylinder and provided with a circumferential groove for interconnecting said slots, a pair of ring members fixed in the open ends of said cylinder and a pair of packing rings provided on the inner surfaces of said ring members for co-operation with said piston in air-tight sealing said cylinder ends, said channel forming part of the fuel-inlet of the idling system being connected by way of secondary channel with the interior of said cylinder at a point near its upper end slightly below its upper ring member.
